UNITED STATES PATENT OFFICE

REINHARD B. BARTELS, OF MELROSE, MASSACHUSETTS

SHOE AND SHOE SOLE AND SHANK STIFFENER THEREFOR

Application filed January 12, 1928. Serial No. 246,163.

This invention relates to the sole portion of shoes, more particularly to the stiffening of the shank portions and has for its main object the stiffening of such portions in a manner which will not interfere with the subsequent lasting of the shoe and wherein special arch supporting characteristics may be embodied if desired.

In the case of welt shoes the stiffeners have heretofore been commonly attached to the lower face of the innersole after the shoe has been lasted. In the case of McKay shoes the stiffeners have usually been fixed to the outer sole. If the stiffener were attached to the innersole prior to the lasting operation, it would interfere with the action of the grippers by which the upper is pulled over the last during the lasting operation.

According to the present invention the stiffener is incorporated in a sole member, preferably the innersole. Where it is incorporated in the innersole this may be done before the innersole is attached to the last and it may be so formed as to cause the upper face of the innersole to be upwardly arched transversely at the proper place to form a metatarsal arch support. If it is desired to form a very stiff shank a supplemental stiffener may be applied to the lower face of the innersole or to the inner face of the outer sole after the lasting operation in the usual manner.

For a more complete understanding of this invention reference may be had to the accompanying drawings, in which

Figure 1 is a perspective showing the stiffener in place on the lower layer or laminated or split innersole, the upper layer being turned back.

Figures 2 and 3 are longitudinal vertical sections through the sole with the stiffener therein before and after the molding operations, respectively.

Figure 4 is a side elevation of a shoe partly in section showing beside the reinforced innersole an additional shank stiffener.

Figure 5 is a section on line 5—5 of Figure 3.

Referring to these drawings, 1 indicates

a sole member which in the embodiment shown is an innersole for a McKay shoe, though it should be understood that it may be the sole of a welt shoe, or in the broader aspects of this invention it may be an outer sole. As shown the rear portion of this innersole is shown laminated, having the two layers 2 and 3. These laminations may be entirely separate and cemented or otherwise fixed together at their forepart or they may be formed integral by splitting the rear portion of the sole inwardly along a plane between its upper and lower faces and to a point preferably somewhat forwardly of the break line of the shoe as indicated at 4. The upper lamination being turned back, a stiffener plate, preferably in the form of a flat steel blank or plate as at 5 is inserted between the laminations, and the upper lamination is then returned to a position overlying the lower lamination and is preferably cemented or otherwise fixed in place. The plate is thus incorporated in the sole member between its upper and lower faces. While the stiffener plate 5 may be held in position solely by the means which attaches the two laminations together, it may be attached if desired to either one or both of the laminations. As shown it is provided with prongs at the points 6, 7 and 8 which may be driven into and clinched in one of the laminations, as the lower lamination 2, thus to fix the stiffener 5 to this lamination. Attachment of the stiffener in this manner prevents any possibility of the plate slipping from its proper position after its insertion.

Preferably the plate is flat when placed in position as shown in Figures 1 and 2 and after it is incorporated in the sole member the sole member and the stiffener are molded together to the desired contour.

As shown in Figures 3 and 5, this contour may comprise an upwardly arched longitudinal curve at the shank portion 10 and at its extreme forward end a laterally arched portion as at 11 shaped and positioned to cause the upper face of the innersole to form a metatarsal arch support for the foot of the wearer. The stiffness of this plate 5 when thus molded to shape may be relied upon

- entirely to produce the proper stiffness of the shank, or if it is desired to produce an extremely stiff shank, the shank portion of the shoe may be further reinforced by a shank stiffener located between the inner and outer soles as shown at 15 in Figure 4. This shank stiffener located between the soles acts also to center the outersole laterally of the shoe. By dividing the stiffening action between a portion within the inner-sole and a portion between the inner and outersoles, both the advantage of a shaped sole form to which the upper may be lasted and a centering function for the outersole are secured.
- 15 Where the stiffener 5 is incorporated in the innersole it does not protrude from the lower face of the innersole to interfere with the action of the grippers commonly em-
ployed in laying the upper over the sole
20 during the lasting operation, and yet it makes possible the reinforcing of the shank portion prior to the fixing of the innersole on the last, so that its proper shaping to the desired contour prior to the lasting oper-
25 ation may be insured.

Having thus described certain embodiments of this invention, it should be evident to those skilled in the art that various changes and modifications might be made 30 therein without departing from its spirit or scope as defined by the appended claim.

I claim:

A shoe having inner and outer soles, said 35 innersole being laminated, a plate between said laminations shaped to produce an upwardly convex face to said innersole and positioned to form a metatarsal arch support, and a shank reinforcement between said soles underlying said plate.

40 In testimony whereof I have affixed my signature.

REINHARD B. BARTELS.
